HEEL ATTACHING MACHINE

Joseph Welton Carr and Thomas Baggott Clarke,
Leicester, England, assignors to United Shoe
Machinery Corporation, Borough of Flemington,
N. J., a corporation of New Jersey

Application January 6, 1943, Serial No. 471,412
In Great Britain February 11, 1942

28 Claims. (Cl. 12—19.2)

The present invention is concerned with improvements in the heelng of shoes, the term shoe being used herein to indicate outer footwear generally and the term heel to indicate either a completed heel or a heel-body which is not necessarily completed. By way of illustration, the invention will be herein disclosed with reference to its application to means suitable for use in carrying out a process of attaching together a heel and a shoe, wherein a plurality of fasteners are inserted into one of the parts, leaving portions of the fasteners projecting, and the shoe and heel thereafter pressed together so that the portions of the fasteners projecting enter the other part. Such a process may combine benefits of both inside heel-attaching and of outside heel-attaching. It enables, as is the case with outside attaching, the shoe to remain on its last during the attaching operation, and also as with inside attaching, the heel to have a top-piece pre-attached. Hitherto, in carrying out such a process, the operation of inserting the fasteners into one of the parts and the operation of pressing the parts together have been effected in separate machines. It is an object of the present invention to provide a single machine, so arranged that both operations may be effected therein. It is however to be appreciated, that features of the invention may also find application in machines not necessarily arranged to effect both operations.

The invention will hereinafter be described in connection with an illustrative machine comprising means for inserting fasteners in the heel-seat of a shoe, and means for pressing together the shoe with its fasteners and a heel to cause the attachment of said heel. Preferably, the fastener-inserting means also acts to mold the heel-seat of the shoe, and means is provided for supplying fasteners to said inserting means. The machine may include a shoe-support having a work-positioning band-clamp and a jack or abutment. Slidable transversely of the machine and positioned below the band-clamp and abutment is a carrier upon which two operating mechanisms are spaced transversely. The carrier is so movable as to position either of the mechanisms in registration with the shoe-support. One of the mechanisms may take the form of a die-and-driver-assembly, including a nailing die provided with a molding surface and in which operate drivers. Distributing means is provided for supplying to the die a load of nails or other fasteners under the control of the carrier. Before the nails are driven into the heel-seat of the supported shoe, pressure is applied between the shoe-

support and the die to subject said heel-seat to compression to mold it to a shape for the reception of the attaching surface of the heel. During the time the shoe is acted upon by the nailing and molding mechanism, it is held in position by the band-clamp. After the nails have been driven, pressure between the shoe-support and the nailing die is relieved, but the shoe is still held clamped under the control of the carrier.

10 The other operating mechanism furnishes a heel-holder, which by movement of the carrier is brought into registration with the shoe-support. Pressure is then exerted between the heel-holder and the shoe-support to cause the shoe and heel to be pressed together to cause attachment of the heel. The operation of the machine may be so controlled by the position of the carrier, that it can occur only when one of the operating mechanisms is in registration with the shoe-support.

20 In the accompanying drawings,
Fig. 1 is a broken side elevation taken from the left of the illustrative machine;

Fig. 2, a front elevation of the elements more closely related to the present invention, with the 25 work-engaging mechanisms respectively in their nail-receiving and heel-applying positions;

Fig. 11, a view similar to Fig. 1, with the elements positioned for the pressing of a heel upon 45 the heel-seat of a shoe; and

Figs. 12 and 13 are enlarged vertical sections, illustrating, respectively, the steps of nail-insertion and heel-attachment.

50 Portions of the illustrative machine are similar in many respects to the machine disclosed in Letters Patent of the United States No. 2,259,568, Kestell et al., October 21, 1941. There is similarly a band-clamp 1 (Fig. 1) arranged to engage the back and sides of the heel-portion of the upper of a shoe and to enter the crease

formed between the upper and outsole. To furnish, with the band-clamp, a shoe-support, there is also a last-engaging abutment or shoe-pressing jack consisting of a member 3 for engaging the crown of a last applied to the lower end of a post 5 pivoted at 7 in a slide 9. This slide is mounted for fore and aft movement in a guideway formed in the underside of a plate 11 which is carried on the lower end of a plunger 13. The plunger is arranged to be moved heightwise of the machine to cause the abutment 3 to press against a last, and the band-clamp 1 is mounted to partake of the movement of the plunger. For this purpose, there is threaded into a trunnion upon the plate 11 the upper end of a link 15, the lower end of which is threaded into a trunnion-block 17 on means carrying the band-clamp. The link 15 has left and right screw-threads on its ends to provide for determining the heightwise position of the band-clamp. Inasmuch as the band-clamp-supporting mechanism of the present illustrative machine is similar to that described in the previously mentioned patent, no further description of it need be given. For operating this mechanism there is provided a rod 19 pivoted at its rear end to the upwardly extending arm of a bell-crank-lever 21 fulcrumed at 23 on the frame of the machine. The bell-crank-lever has a forwardly extending arm 25 to which is pivotally connected the upper end of a rod 27, which at its lower end passes through the fulcrum-stud 29 of a lever 31, this stud being mounted in the frame of the machine. A spring 33 surrounds the rod 27 between the lever 31 and a collar 35 fast on the rod, thereby serving to swing the lever 21 in a direction to cause arms of the band-clamp to be moved into clamping relation. Latching means is provided to hold the spring 33 in condition ready to thus move the band-clamp. This latching means (Figs. 1 and 9) comprises an upwardly extending bar 37 connected at its lower end to the forward end of the lever 31, and a downwardly extending rod 39 connected to the rear end of the lever 31 and at its lower end portion to a clutch-throwout-lever 40. A small spring 41 serves to swing the bar 37 rearwardly of the machine to cause a latch-plate 43 on the bar to engage a wear-plate 45 on the forward arm of the lever 21 to hold the spring 33 in compression and the band-clamp open. For moving the bar 37 to free the lever 21 for actuation by the spring 33, said bar has a pawl 47 pivoted thereon and connected by the spring 41 to the frame, it thus being held in contact with a shoulder on a block 49 secured to a horizontally extending rod 51. The rod 51 is pivotally connected to a member 53 secured to the left-hand end of a shaft 55 rock through a link 54 upon depression of a machine-treadle 56. To the upper end of the bar 37 is secured a forwardly extending latch-bar 57 (Figs. 2 and 3), having a latching shoulder 58 formed on its forward end-portion for a purpose later to be described.

From the front of the machine-column projects a bracket 59 having a vertical passage in which is guided a plunger 69 reciprocated under power (Figs. 2, 9 and 10). Extending transversely of the machine and attached to the front face of said bracket is a horizontal guide-rail 61. Situated behind this guide-rail are two other guide-rails 63 (Fig. 3), which extend transversely of the machine in the same vertical plane, each guide-rail 63 having at its inner end a forwardly and rearwardly projecting arm 65

through which pass clamping bolts 67 engaging the bracket 59. To give further support to the guide-frame formed by the three guide-rails, each of the two rear rails 63 is secured at its outer end to the upstanding arm of one of two U-shaped frames 69, 69, and the outer ends of the front guide-rail 61 are respectively secured to the other upstanding arms of these frames (Fig. 1). The crossbars of the frames are bolted to the upper portions of supporting struts 71 secured at their lower ends to the machine-frame. A frame 73, furnishing a carriage or carrier, comprises two transversely extending members 75 situated one behind the other and supported by four rollers 77 riding on the guide-rails 61, 63, 63, it being slidable transversely of the machine. For so moving the frame 73, there is joined to a rod 80 mounted at its left-hand end the ends of a pair of toggle-links 79, which at their outer ends are pivotally connected to a second pair of toggle-links 81. The outer ends of the toggle-links 81 are secured by bolts 83 to a member 85 attached to a spindle 87 journaled in the upper portions of the upstanding arms of the left-hand frame 69. The forward end of the spindle 87 extends beyond the rail 61 and has secured thereon a crank 89 by which the toggle-links 81 may be oscillated to cause the frame 73 to be moved transversely of the machine.

At each end of the frame 73 is mounted a work-engaging and operating mechanism, these mechanisms having different functions. The right-hand work-engaging mechanism 91 comprises a gang-nailing die and mold including a hollow post 93 with an upper section or top-plate 95. Mounted for vertical movement in the post is a plunger 97 (Fig. 2), having at its upper end a plate 99 holding a plurality of vertical nail-drivers 101. The drivers operate in passages 103 through the top-plate 95 and are all provided at their upper ends with conical recesses 105 for a purpose later to be described. Extending downwardly from the plunger 97 is a stem 107. The post 93 is secured in a boss 109 on the frame 73, the right-hand lower end of the boss having a downwardly and inwardly inclined extension or stop member 111 formed thereon. The upper surface of the top-plate 95 is concave, to be complementary to the convex curvature which is generally desirable for the heel-seat of a shoe. The plate thus furnishes a mold, by pressure against which the heel-seat of a shoe may be formed.

The left-hand work-engaging mechanism is indicated at 113 and comprises a heel-holder and pressure means, including a hollow post 115 having formed in its side walls and near the top forwardly and rearwardly extending guideways 117 (Fig. 2). Tongues 119 formed on the side walls of a pressure-block 121 are loosely received in the guideways 117. Movable vertically in the post 115 is a plunger 123 having a downwardly extending stem 125. The head of the plunger is provided with ways receiving a block 127 having three upstanding dowel-pins 129. Mounted on the dowel-pins is a striker-plate 131, the arrangement being such that by sliding the block 127 on the head of the plunger 123 and out of the post 115, the striker-plate 131 may readily be exchanged for one of a different shape, the purpose of this being herein-after explained. The upper face of the pressure-block 121 carries a heel-holder means 133, best shown in Fig. 3. It comprises an abutment 135 adjustably mounted on the plate 121 for engag-

ing the rear of a heel, a pair of fingers 137 for engaging the sides of the heel adjacent to the rear, a second pair of fingers 139 for engaging the sides of the heel adjacent to the breast and a heel-breast-engaging abutment 141. The abutment 141 is pivoted midway of its length on the transverse arm 143 of an L-shaped slide 145, mounted for fore and aft sliding movement on the plate 121. The right-hand end of the arm 143 is received in a slot in a guide 147 upon the plate 121, while the other arm of the slide 145 is guided in a cover-plate 149 (Fig. 6). The fingers 137 are each pivoted on the arm 143 by studs 151 and have intermeshing teeth 153, so that simultaneous movements about the pivot-studs of both fingers may be caused by actuation of an extension 155 from the left-hand finger 137. A spring 157 secured to the extension and to the cover-plate urges the fingers 137 inwardly towards each other, such inward movement being limited when no heel is present by engagement of the extension with the forward end of the cover-plate. The fingers 139, like the fingers 137, are pivoted on the studs 151 and have intermeshing teeth to cause them to move simultaneously and equally, and are urged inwardly by a spring 159 (Fig. 1) connected similarly to the spring 157. The left-hand finger 139 is provided with a forward projection having an upstanding lug 161 receiving contact of a projection 163 formed on the left-hand finger 137, the construction therefore being such that both sets of fingers 137 and 139 are actuatable by the same finger-extension 155. The slide 145 is urged rearwardly of the machine by the two springs 157 and 159, and to limit this movement there is threaded through a lug 165 on the plate 121 a stop-screw 167, against which the rear end of the slide abuts. Near its front the slide is provided with an upstanding pin 169, lying in the path of the extension 155 when the latter is actuated to open the fingers 137 and 139. Upon contact of the extension with the pin, the slide will be forced forwardly to carry the fingers and the breast-engaging abutment 141 away from the rear end abutment 135, thereby facilitating the entry of a heel between the abutments and the fingers. For holding the fingers and the abutment 141 in this position, there is secured to the cover 149 a hollow casing 171 (Fig. 6) in which is located a spring-pressed ball 173. This, when the slide 145 is shifted forwardly as above described, enters a recess 175 in the slide to maintain it in such forward position. It will be appreciated that the two sets of fingers 137 and 139 and the abutments 135 and 141 conveniently determine the position of a heel on the slide 121 and hold it securely. The post 115 has a downwardly and inwardly inclined stop-extension 177 (Fig. 2) formed at its left-hand lower face. Projecting to the right from its upper end is a latch-tripping member 179, adapted to co-operate, in a manner that will hereinafter become clear, with a clutch-tripping latch 219 of the fastener-supplying mechanism D with which the illustrative machine is provided.

The fastener-supplying mechanism operates in a manner generally similar to that described in Letters Patent of the United States No. 1,005,303, Pope, October 10, 1911. It comprises a rotary drum (not shown), which is adapted to discharge fasteners on the upper end of a reciprocating raceway 181 (Fig. 7) having a plurality of fastener-receiving grooves. The nails or other fasteners are delivered to a discharge device con-

sisting of an elongated roll 183, extending transversely of the machine and having a series of passages 185 into which fasteners are introduced from the raceway-grooves. The leading ends of the fasteners project from the passages and abut against a stop-plate 189. This stop-plate is extended somewhat heightwise of the discharge device, since the fasteners intended to be used in the illustrative machine are nails pointed at both ends. Hence there is a tendency for succeeding nails to override the trailing points of the nails in the discharge device and to find their way on to its upper portion. When the discharge device is rotated to deliver its load of nails into fastener-receiving conduits 227, the overriding nails might, if not prevented from doing so, either fall into such conduits or prevent rotation of the discharge device. The stop-plate 189 is adjustable, as hitherto, toward and from the discharge device by a shaft 191 which carries two pinions meshing with racks 193 on the stop-plate.

Rotation of the discharge device 183 to cause fasteners introduced therein to be deposited in the fastener-conduits 227 is caused by a cam-surface 195 (Figs. 2 and 8) formed on the front of a disc 197. The disc is connected by a link and lever (not shown) to a crank secured at the right-hand end of the discharge device. The disc is rotated only at such time as the load of fasteners in the discharge device is to be delivered to the fastener-conduits, and for this purpose it furnishes the driven member of an auxiliary friction-clutch, the driving member of which is mounted on a constantly driven shaft 199. A spring (not shown) serves to urge the disc 197 into contact with the said driving member, but rotation of the disc is normally prevented by a stop-projection 201 formed on the periphery of the disc and contacting with the end of a stop-bar 203. The opposite end of the stop-bar is pivoted to a crank 205, fast upon the rear end of a rocker-shaft 207 journaled in brackets depending from the framework of the fastener-supplying mechanism. To the forward end of this shaft is secured a transversely extending rocker arm 209, connected by a link 211 to a transversely extending lever 213 (Fig. 2) fulcrumed between its ends by a stud 215 upon a bracket 217 attached to the machine-column. The opposite end of the lever has a depending latch 219 pivoted thereto, and engaged by the latch-tripping member 179 on the post 115 at certain times, as will later appear. A spring 221 (Fig. 8), connected at one end to the stop-bar 203 and at its other end to the frame of the fastener-supplying mechanism, serves normally to hold the stop-bar in the path of the projection 201 on the disc 197 and the latch member 219 in position to be engaged by the latch-tripping member 179.

The fastener-supplying mechanism D is provided with a series of fastener-stops 223 (Fig. 7) which, when the discharge-roll 183 is rotated to deliver a load of fasteners, are allowed to descend by their own weight into contact with the lower-most fasteners in the raceways to hold them against downward movement. The fastener-stops are secured to a rock-shaft 225, the oscillation of which is controlled by the discharge-roll. The fastener-receiving conduits 227 into which fasteners are discharged by the roll 183 are connected by flexible fastener-guiding tubes 229 to a carrier-bar 231 (Fig. 2) extending forwardly from the machine-column. Slidably mounted in grooves in the bar is the upper portion 233 of a guide-tube-assembly or mug 235.

This upper portion is connected to the main body portion of the mug by a web 237, which forms a convenient handle by which the mug may be removed from the bar 231. Flexible fastener-guiding tubes 239 connect the upper and lower portions of the mug, the arrangement being such that fasteners delivered into the conduits 227 pass through the tubes 229 and 239 for delivery. This mug occupies such a position at the front of the machine that it lies just above the work-engaging mechanism 91 when the sliding frame 73 is moved to the right. Incidentally, when the device 91 occupies this position the heel-engaging mechanism 113 is immediately beneath the band-clamp 1 of the machine. This is as appears in Fig. 2. Fasteners delivered through the mug 235 will pass into the driver-passages 103 in the top-plate 95 of the post 93. It will be understood that different top-plates may be provided for different types and kinds of heels where different nailing designs are required, and that mugs 235 corresponding in design may readily be substituted.

Secured to the outer face of the forward transversely extending member 75 of the sliding frame 73 is a bar 241, forming part of safety means of the machine. Secured to the front guide-rail 61 is a casing 243 having a vertical guideway in which is movable a safety-latch 245 (Figs. 4 and 5). On the rear lower end portion of the latch is a shoulder 247 for engagement with the edge of a cover-plate 249 for the casing 243. This limits the upward movement of the latch under the influence of a tension-spring 251. The lower end of the latch is joined by a rod 253 to the treadle of the machine. There is provided in the rear of the latch a notch 255 of just sufficient size to allow the bar 241 to pass therethrough. This bar is of such length that when either of the two work-engaging mechanisms 91 and 113 is positioned by the frame 73 for operation beneath the band-clamp, its corresponding end is just clear of the notch 255, so that the latch will not impede movement of the treadle to set the machine into operation as hereinafter described. On the other hand, if the frame is so located that neither of the work-engaging mechanisms is thus positioned, the bar 241 will lie in the notch 255 to prevent depression of the treadle and setting of the machine into power-operation.

The illustrative machine is particularly suitable for use in carrying out that method of heel-ing shoes, which comprises inserting a plurality of nails in the heel-seat but leaving portions protruding therefrom, said nails being inserted while consolidating pressure is applied between the outside and interior surfaces of the heel-seat. Thereafter, the shoe and a heel are pressed together to cause the protruding nails to enter the heel to secure it to the shoe. Conveniently, the nails employed in this method are without heads and collars or like means to control the depth of insertion and are pointed at both ends. In using the machine a quantity of nails for carrying out this method are supplied to the drum of the fastener-supplying mechanism of the machine. Assuming that a gang of such nails N (Fig. 12) have been introduced into the passages 103 of the top-plate 95 of the work-engaging mechanism 91, when the elements were as illustrated in Fig. 2, the sliding frame 73 will be moved to the left to carry this mechanism into operating position beneath the band-clamp 1 (Fig. 10). Here, the post will register with the bracket 59 and the

stem of the plunger 97 with the power-operated plunger 60. To ensure that the post 93 will properly occupy this position, the stop 111 on the boss 109 contacts with a complementally-shaped face 257 on the bracket 59. The operator will then take a shoe S (Figs. 11 and 12), which is preferably upon a last L having the usual metal plate I at its heel-seat-portion, said shoe having either a full-length outsole extending to the end of the shoe-bottom or an outsole which extends only just beyond the heel-breast-line and to which is joined a piece-sole at the remainder of the heel-seat, apply it to the post 5, and position it bottom-down between the open arms of the band-clamp. He will then depress the machine-treadle. The first part of the depression of the treadle will cause rocking of the shaft 55, lowering the last-engaging abutment 3, together with the band-clamp 1, toward the post 93 to cause the heel-seat to be pressed against the mold-plate 95 with preliminary pressure. Just prior to the actual pressing of the shoe against the plate, the rod 51 will be moved forward to shift the latch-plate 43 on the bar 37 away from the wear-plate 45 on the bell-crank-lever 21. This allows the spring 33 to so move the lever as to cause the arms of the band-clamp to engage the shoe (Fig. 11). Further depression of the treadle will trip the clutch of the machine to initiate its power-operation. During this power-operation the last-engaging abutment 3 will be lowered to cause the shoe to be pressed more firmly against the plate 95, thereby subjecting the material at the heel-seat to considerable compression. Owing to the convexity of the plate, it exerts a molding action on the heel-seat to impart thereto the proper form for the reception of the cupped attaching surface of a heel. This action is maintained while the nails are driven, to ensure that the layers of material at the heel-seat will not separate or gape under the driving force. The nail-driving operation occurs as a result of upward movement of the plunger 60 in the bracket 59, this plunger engaging the downwardly extending stem 107 on the driver-carrying plunger 97. The extent of upward movement of the drivers 101 is such that the nails are preferably driven into the heel-seat until their entering ends contact with the last-plate, so these ends may be clinched slightly. The nails are preferably of such length, that, after driving, a portion of each nail at least equal to that which has entered the heel-seat will be left projecting from it. It will be appreciated that by providing fastener-drivers having conically-recessed end portions 105, more control of the double-pointed nails will be attained than would be the case if normal flat-ended drivers were to be used.

As the work-engaging mechanism 91 was moved into operating position, an upstanding latch member 259 (Fig. 2) on the sliding frame 73 engaged the latching shoulder 58 on the forwardly extending latch-bar 57 of the band-clamp. As the machine comes to the end of its power-operation, the clutch throw-out lever 40 will be moved, and, through the rod 39, lever 31, bar 37, latch-plate 43 and lever 21 will tend to open the arms of the band-clamp and cause the compression-spring 33 to be loaded. However, due to the engagement of the latch-member 259 with the latching shoulder on the bar 57, the bar 37 will be held against the action of its spring 41 from moving rearwardly to position the wear-plate 43 above the latch-plate. Therefore, as the machine comes to a stop the band-clamp will

remain in clamping engagement with the shoe into the heel-seat of which nails have just been driven.

The operator will now place a heel H (Fig. 13), which may be built up from a plurality of lifts, having a top-piece secured thereto and which has been both compressed and breasted, tread-end down and with its breast-face to the front, in the heel-holder 133 of the device 113. He will then move the frame 73 to the right to carry the work-engaging mechanism 91 from and to bring the work-engaging mechanism 113 into operating position (Fig. 2). This position is determined by engagement of the stop-extension 177 of the mechanism 113 with a complementally-shaped face 261 on the bracket 59 (Fig. 2). Depression of the treadle will then cause the last-engaging abutment 3 to be lowered, and since the shoe is held by the band-clamp (Fig. 11), the operator will not be called upon to exercise any great care in the determination of the relative positions of the shoe and heel, the relation being determined by the heel-holder means and the band-clamp. Power-operation of the machine, upon further depression of the treadle, will cause the last-engaging abutment to press firmly upon the last. This causes the descent of the shoe, so that the nails N protruding from the heel-seat will be thrust into the heel until the heel-seat and cup of the heel are brought firmly into contact (Fig. 13). The plunger 60 will also be moved upwardly to cause the stem 125 on the plunger 123 of the heel-engaging mechanism 113 to move, through the block 127 and striker-plate 131 thereon, the pressure-block 121 of the device upwardly. This movement is possible because of the loose fit of the tongues 119 in the guideways 117. It will increase the pressure exerted between the heel and shoe and will ensure firm attachment. Further, if it is desired to exert more pressure between the forward breast-portion of the heel and the heel-seat than at the rear, the striker-plate 131 may readily be exchanged for one of a different form, as wedge-shaped with its upper surface tapering rearwardly and downwardly.

As the machine nears the end of its power-operation, the arms of the band-clamp will be opened and latched in this condition thereby releasing the shoe for removal from the machine. This follows, since in moving the frame 73 to the right to bring the heel-supporting device 113 into operating position, the latch member 259 will have been moved away from the latching-shoulder on the bar 57. As the frame is moved to the right, the latch-tripping member 179 will engage and move the depending latch member 219. This will cause the lever 213 to rock in a clockwise direction (Fig. 2), moving the stop-bar 203 away from the stop-projection 201 on the periphery of the disc 197 to allow the disc to be rotated. The roll 183 of the fastener-supplying mechanism is therefore rotated to allow the nails delivered by the raceways 181 to the passages 185 to be deposited in the fastener-conduits 221. From the fastener-conduits the nails will pass through the mug 235 to the post 93, in readiness for succeeding operation.

Having thus described our invention, what we claim as new and desire to secure by Letters Patent of the United States is:

1. In a heel-attaching machine, means for inserting fasteners in the heel-seat of a shoe, and means for pressing together the shoe with its fasteners and a heel to cause the attachment of said heel, the fastener-inserting means and press-

ing means and the work being movable relatively to one another to permit the successive operations upon said work.

5 2. In a heel-attaching machine, means for molding the heel-seat of a shoe and for inserting fasteners in said heel-seat, and means for pressing together the shoe with its fasteners and a heel to cause the attachment of said heel, the heel-seat-molding and fastener-inserting means and pressing means and the work being movable relatively to one another to permit the successive operations upon said work.

10 3. In a heel-attaching machine, means for inserting fasteners in the heel-seat of a shoe, means for pressing together the shoe with its fasteners and a heel to cause the attachment of said heel, the fastener-inserting means and pressing means and the work being movable relatively to one another to permit the successive operations upon said work, and means for supplying fasteners to the inserting means.

15 4. In a heel-attaching machine, a shoe-support, heel-seat-molding and fastener-inserting mechanism, means for applying pressure between the shoe-support and said mechanism to mold the heel-seat of a supported shoe, means for inserting fasteners in said heel-seat, a heel-holder, and means for forcing together a heel in the holder and the supported shoe with its fasteners to cause the attachment of the heel, the molding and inserting mechanism and the heel-holder and forcing means on the one hand and the work on the other being movable relatively to one another to permit the successive operations upon the work.

20 5. In a heel-attaching machine, a shoe-support, heel-seat-molding and fastener-inserting mechanism, heel-holding mechanism, the two mechanisms being mounted for movement together to present either in operating position at the shoe-support, and means for producing relative movement between the shoe-support and the two mechanisms to first mold the heel-seat of a supported shoe and to insert fasteners therein and then to force together a heel and the inserted fasteners to cause the attachment of the heel.

25 6. In a heel-attaching machine, a shoe-support, heel-seat-molding and fastener-inserting mechanism, heel-holding mechanism, the two mechanisms being mounted for movement together to present either in operating position at the shoe-support, means for producing relative movement between the shoe-support and the two mechanisms to first mold the heel-seat of a supported shoe and to insert fasteners therein and then to force together a heel and the inserted fasteners to cause the attachment of the heel, and means acting to permit the relative movement only when one of the mechanisms is in operating position.

30 7. In a heel-attaching machine, a shoe-support, fastener-inserting mechanism, a heel-holder, the shoe-support and the fastener-inserting mechanism and heel-holder being mounted for relative movement to first cause the presentation in one position of the heel-seat of a supported shoe to the fastener-inserting mechanism and then to the heel-holder in a second position, a member movable to insert fasteners in the heel-seat of the supported shoe at the first position, and means for producing relative movement between the shoe-support and heel-holder to press together a heel and the inserted fasteners in the second position.

35 8. In a heel-attaching machine, a shoe-sup-

port, fastener-inserting mechanism, a heel-holder, the shoe-support and the fastener-inserting mechanism and heel-holder being mounted for relative movement to first cause the presentation in one position of the heel-seat of a supported shoe to the fastener-inserting mechanism and then to the heel-holder in a second position, and a member movable to insert fasteners in the heel-seat of a supported shoe at the first position and to press together a heel and inserted fasteners in the second position.

9. In a heel-attaching machine, a shoe-support, fastener-inserting mechanism, a heel-holder, the shoe-support and the fastener-inserting mechanism and heel-holder being mounted for relative movement to first cause the presentation in one position of the heel-seat of a supported shoe to the fastener-inserting mechanism and then to the heel-holder in a second position, a member movable to insert fasteners in the heel-seat of a supported shoe at the first position and to press together a heel and inserted fasteners in the second position, and means for producing relative movement between the shoe-support and heel-holder to press together the heel and the inserted fasteners in the second position.

10. In a heel-attaching machine, a shoe-support, fastener-inserting mechanism having a molding member, a heel-holder, the shoe support and the fastener-inserting mechanism and heel-holder being mounted for relative movement to first cause the presentation in one position of the heel-seat of a supported shoe to the fastener-inserting mechanism and then to the heel-holder in a second position, a member movable to insert fasteners in the heel-seat of the supported shoe at the first position, and means for producing relative movement between the shoe-support and fastener-inserting mechanism to mold the heel-seat of a supported shoe in the first position and between said shoe-support and heel-holder to press together a heel and the inserted fasteners in the second position.

11. In a heel-attaching machine, a shoe-support, fastener-inserting mechanism, a heel-holder, the shoe-support and the fastener-inserting mechanism and heel-holder being mounted for relative movement to first cause the presentation in one position of the heel-seat of a supported shoe to the fastener-inserting mechanism and then to the heel-holder in a second position, a member movable to insert fasteners in the heel-seat of the supported shoe at the first position, means for producing relative movement between the shoe-support and heel-holder to press together a heel and the inserted fasteners in the second position, and means for delivering fasteners to the inserting mechanism.

12. In a heel-attaching machine, a shoe-support, a die-and-driver-assembly, the die having a molding depression, a heel-holder, the shoe-support and the die-and-driver-assembly and heel-holder being mounted for relative movement to first cause the presentation at one position of the heel-seat of a supported shoe to the die and then to the heel-holder in a second position, and means movable under the power of the machine to actuate the drivers in the first position to insert fasteners in the heel-seat of the supported shoe and to mold the heel-seat and to press together a heel and inserted fasteners in the second position.

13. In a heel-attaching machine, a shoe-support, fastener-inserting mechanism, a heel-holder, the shoe-support and the fastener-inserting

mechanism and heel-holder being mounted for relative movement to first cause the presentation in one position of the heel-seat of a supported shoe to the fastener-inserting mechanism and then to the heel-holder in a second position, a member movable to insert fasteners in the heel-seat of the supported shoe at the first position, means for producing relative movement between the shoe-support and heel-holder to press together a heel and the inserted fasteners in the second position, and means operating in the second position for delivering fasteners to the inserting mechanism.

14. In a heel-attaching machine, a shoe-support, a carrier, a die-and-driver-assembly and a heel-holder mounted upon the carrier, said carrier being movable first to present the die-and-driver-assembly to the shoe-support and then the heel-holder to said support, and a member movable successively to actuate the drivers to insert the fasteners in the heel-seat of the supported shoe and to press together a heel and the inserted fasteners.

15. In a heel-attaching machine, a shoe-support, a carrier, a die-and-driver-assembly and a heel-holder mounted upon the carrier, said carrier being movable first to present the die-and-driver-assembly to the shoe-support and then the heel-holder to said support, a member movable successively to actuate the drivers to insert the fasteners in the heel-seat of the supported shoe and to press together a heel and the inserted fasteners, and means acting upon the carrier to permit movement of the member only when either the die-and-driver-assembly or the heel-holder is presented to the support.

16. In a heel-attaching machine, a carrier, a die-and-driver-assembly and a heel-holder mounted upon the carrier, said carrier being movable into two positions, a shoe-support to which the die-and-driver-assembly is presented in one position of the carrier and to which the heel-holder is presented in the second position of the carrier, a member movable when the carrier is in the first position to actuate the drivers of the assembly to insert nails in the heel-seat of a supported shoe, and means for moving the shoe-support when the carrier is in the second position to press together the inserted nails and a heel in the holder.

17. In a heel-attaching machine, a carrier, a die-and-driver-assembly and a heel-holder mounted upon the carrier, the die of the assembly having a molding depression, said carrier being movable into two positions, a shoe-support to which the die-and-driver-assembly is presented in one position of the carrier and to which the heel-holder is presented in the second position of the carrier, a member movable when the carrier is in the first position to actuate the drivers of the assembly to insert nails in the heel-seat of a supported shoe, and means for moving the shoe-support when the carrier is in the first position to press the heel-seat of the supported shoe against the molding depression and for moving said shoe-support when the carrier is in the second position to press together the inserted nails and a heel in the holder.

18. In a heel-attaching machine, a shoe-support, a carrier, a die-and-driver-assembly and a heel-holder mounted upon the carrier, said carrier being movable first to present the die-and-driver-assembly to the shoe-support and then the heel-holder to said support, a member movable successively to actuate the drivers to insert nails

in the heel-seat of a supported shoe and to press together a heel and the inserted nails, and means made effective in the movement of the carrier for delivering nails to the die-and-driver-assembly.

19. In a heel-attaching machine, a shoe-support including a band-clamp arranged to open and close upon a supported shoe, a carrier movable into two operating positions, a die-and-driver-assembly and a heel-holder mounted upon the carrier, the die-and-driver-assembly being presented to the shoe-support in one position and the heel-holder to said support in a second position, means made effective in successive power-operations of the machine for actuating the die-and-driver-assembly in the first position of the carrier to insert nails in the heel-seat of a supported shoe and in the second position of said carrier to produce relative movement of the shoe-support and heel-holder to press together a heel and the inserted nails, means for opening the band-clamp, and means for preventing such opening after the operation in the first position of the carrier.

20. In a heel-attaching machine, a shoe-support including a band-clamp arranged to open and close upon a supported shoe, a carrier movable into two operating positions, a die-and-driver-assembly and a heel-holder mounted upon the carrier, the die-and-driver-assembly being presented to the shoe-support in one position and the heel-holder to said support in a second position, means made effective in successive power-operations of the machine for actuating the die-and-driver-assembly in the first position of the carrier to insert nails in the heel-seat of a supported shoe and in the second position of said carrier to produce relative movement of the shoe-support and heel-holder to press together a heel and the inserted nails, and means effective only when the carrier is in operating position for controlling the power-operation of the machine.

21. In a heel-attaching machine, a shoe-support including a band-clamp arranged to open and close upon a supported shoe, a carrier movable into two operating positions, a die-and-driver-assembly and a heel-holder mounted upon the carrier, the die-and-driver-assembly being presented to the shoe-support in one position and the heel-holder to said support in a second position, means made effective in successive power-operations of the machine for actuating the die-and-driver-assembly in the first position of the carrier to insert nails in the heel-seat of a supported shoe and in the second position of said carrier to produce relative movement of the shoe-support and heel-holder to press together a heel and the inserted nails, means for opening the band-clamp, and means controlled by the carrier for preventing such opening after the operation in the first position of the carrier.

22. In a heel-attaching machine, a frame having a horizontal guideway, a shoe-support including a jack and a band-clamp carried upon the frame, a carriage movable upon the guideway, two posts rising from the carriage and movable thereby into registration with the shoe-support, a heel-seat-molding die mounted upon one post, nail-drivers movable in said post in co-operation with the die, a heel-holder movable upon the other post, and a plunger reciprocating in the frame beneath the carriage in registration with the shoe-support and acting upon the drivers and the heel-holder.

23. In a heel-attaching machine, a frame hav-

ing a horizontal guideway, a shoe-support including a jack and a band-clamp carried upon the frame, a carriage movable upon the guideway, two posts rising from the carriage and movable thereby into registration with the shoe-support, a heel-seat-molding die mounted upon one post, nail-drivers movable in said post in co-operation with the die, a heel-holder movable upon the other post, a plunger reciprocating in the frame beneath the carriage in registration with the shoe-support and acting upon the drivers and the heel-holder, means for controlling the power-operation of the machine, and a latch co-operating with the carrier and permitting actuation of the controlling means only when one of the posts is in registration with the shoe-support.

24. In a heel-attaching machine, a frame having a horizontal guideway, a shoe-support including a jack and a band-clamp movable upon the frame, a carriage movable upon the guideway, two posts rising from the carriage and movable thereby into registration with the shoe-support, a heel-seat-molding die mounted upon one post, nail-drivers movable in said post in co-operation with the die, a heel-holder carried by the other post, the shoe-support in its movement forcing the heel-seat of a supported shoe against the die and against a heel in the holder, and a plunger reciprocating in the frame beneath the carriage in registration with the shoe-support and acting upon the drivers.

25. In a heel-attaching machine, a frame having a horizontal guideway, a shoe-support including a jack and a band-clamp movable upon the frame, a carriage movable upon the guideway, two posts rising from the carriage and movable thereby into registration with the shoe-support, a heel-seat-molding die mounted upon one post, nail-drivers movable in said post in co-operation with the die, a heel-holder carried by the other post, the support in its movement forcing the heel-seat of a supported shoe against the die and against a heel in the holder, and a plunger reciprocating beneath the carriage in registration with the shoe-support and acting upon the drivers and the heel-holder.

26. In a heel-attaching machine, a frame having a horizontal guideway, a shoe-support including a jack and a band-clamp carried upon the frame, a carriage movable upon the guideway, two posts rising from the carriage and movable thereby into registration with the shoe-support, a heel-seat-molding die mounted upon one post, nail-drivers movable in said post in co-operation with the die, a heel-holder upon the other post for co-operation with the shoe-support, a nail-distributor arranged to deliver to the die when the heel-holder is in registration with the shoe-support, and means controlled by the carriage upon the movement of the heel-holder into registration with the shoe-support for causing such nail-delivery.

27. In a heel-attaching machine, a frame having a horizontal guideway, a shoe-support including a jack and a band-clamp carried upon the frame, said band-clamp being arranged to open and close upon a supported shoe, a carriage movable upon the guideway, two posts rising from the carriage and movable thereby into registration with the shoe-support, a heel-seat-molding die mounted upon one post, nail-drivers movable in the post in co-operation with the die, a heel-holder upon the other post for co-operation with the shoe-support, means for opening the band-clamp under the power of the machine

upon movement of the heel-holder into registration with the shoe-support, and a plunger reciprocating in the frame beneath the carriage in registration with the shoe-support and acting upon the drivers and the heel-holder.

28. In a heel-attaching machine, a frame having a horizontal guideway, a shoe-support including a jack and a band-clamp carried upon the frame, said band-clamp being arranged to open and close upon a supported shoe, a carriage movable upon the guideway, two posts rising from the carriage and movable thereby into registration with the shoe-support, a heel-seat-molding die mounted upon one post, nail-drivers

movable in the post in co-operation with the die, a heel-holder upon the other post for co-operation with the shoe-support, means for opening the band-clamp under the power of the machine while the heel-holder is in registration with the shoe-support, means controlled by the carrier for preventing such opening of the band-clamp while the die is in registration with the shoe-support, and a plunger reciprocating in the frame beneath the carriage in registration with the shoe-support and acting upon the drivers and the heel-holder.
